3 Claims

ABSTRACT OF THE DISCLOSURE

A mechanism for stopping a loom when a supply of reserve bobbins has been depleted to a predetermined number. A sensing lever positioned in the path of the bobbins is held in an inactive position when engaged by a bobbin, but in the absence of a bobbin is free to swing and trip an actuating device including a trigger mechanism to cause a blade to engage oscillating bars on the loom, thereby stopping the loom.

The present invention relates generally to textile machinery and more particularly to a mechanism adapted to stop a loom upon a predetermined occurrence.

The present invention is intended for use with looms of the type equipped with a mechanically operated stop mechanism adapted to interrupt operation of the loom in the event one of the warp yarns breaks. Many such looms are equipped with magazines adapted to hold a reserve of wound bobbins awaiting insertion into a shuttle by a bobbin changing mechanism. These magazines can be manually loaded by loom attendants or by use of an automatic bobbin winding machine such as that disclosed in the U.S. Patent No. 2,763,443 issued Sept. 18, 1956.

However, whether the loom magazine is replenished manually or automatically, it may occur that the desired number of reserve bobbins is not maintained. To prevent runout of weft yarn with its attendant difficulties, it is desirable to stop the loom when the number of reserve bobbins has diminished to a predetermined number, but at least while a partially wound bobbin remains in the shuttle. To this end, a pivoted lever positioned in the path of the reserve bobbins in the magazine is normally held in an inactive position when engaged by a bobbin, but in the absence of a bobbin is free to swing, in the course of which it trips an actuating device including a trigger mechanism causing a remotely located blade to drop between the teeth of oscillating drop wire rods on the loom, thereby stopping the loom.

Accordingly, an object of the invention is to provide a new and improved mechanism adapted to stop a loom.

Another object of the invention is to provide a new and improved actuating mechanism responsive to a predetermined condition for stopping the loom. A related object is to provide such a mechanism which is operable when a supply of reserve bobbins has been depleted to a predetermined number.

Yet another object of the invention is the provision of a mechanical actuating mechanism responsive to the depletion of reserve bobbins to a predetermined number for operating a warp stop mechanism of a loom. A related object is the provision of such a construction wherein a blade is selectively movable by the actuating mechanism into engagement with reciprocating bars of the warp stop mechanism, and including a lost motion connection between the blade and the actuating mechanism.

Other and further objects of the invention are obvious or appear in the description which follows, taken together with the accompanying drawings.

2

In the drawings:

FIG. 1 is a fragmentary side elevation view of a portion of a loom embodying the invention;

FIG. 2 is an enlarged top plan view of parts illustrated in FIG. 1;

FIG. 3 is a sectional view taken substantially along line 3—3 in FIG. 2; and

FIG. 4 is a detail view of parts illustrated in FIGS. 1 and 2.

Refer now to the drawings and initially to FIG. 1 illustrating a portion of a loom on a frame F of which is suitably mounted a magazine 10 adapted to hold in reserve a plurality of wound bobbins B. Supported in a stacked relationship, the bobbins B feed downwardly under gravity and when a bobbin in a shuttle S of the loom has been substantially exhausted, a loom hammer 12 is suitably operated to displace the lowermost bobbin from the magazine 10 into the shuttle S, simultaneously causing the exhausted bobbin to be discharged from the shuttle.

In FIG. 1, it is seen that one end of a pivotally mounted lever 14 has a bent over foot 16 which extends into the path of the reserve bobbins B supported in the magazine 10. When a bobbin comes to rest on the foot 16, the lever 14 is held in the raised position as seen in solid lines in FIG. 1. However, when the supply of reserve bobbins B becomes depleted to the extent that one of them no longer rests upon the foot 16, the lever 14 swings in a clockwise direction (FIG. 1) under the urging of a suitable weight 18 fixed to the lever adjacent an end opposite from the foot 16 and assumes a position as indicated by dotted lines. As the lever 14 swings, it strikes a tab 20 of a mechanical actuating device including a trigger mechanism 22 suitably fixed to the frame F and adapted to initiate stoppage of the loom. The foot 16 is preferably positioned in the lower regions of the magazine 10 so that its swinging movement is responsive to a substantial depletion of the reserve bobbins B in the magazine. Of course, it will be appreciated that even if the foot 16 is so positioned that it is not released until the magazine 10 has been entirely depleted, the shuttle S will still contain a substantially fresh bobbin, namely the last bobbin to be transferred out of the magazine 10.

As the lever 14 strikes the tab 20, a latch plate 24 integral with the tab 20 is rocked in a counterclockwise direction (FIG. 1) about a stationary shaft 26 and against the bias of a torsion spring 28 (FIG. 2) coiled about the shaft 26. The ends of the shaft 26 are suitably fixed to the extremities of a U-shaped bracket 30 which is fastened, as by welding, to a support bar 32 which, in turn, is suitably mounted to a frame of the loom.

One end of the torsion spring 28 engages one leg 34 of the bracket 30 and its opposite end engages the latch plate 24. In this manner, the latch plate 24 is urged in a clockwise direction so that a shoulder 36 in a longitudinally extending edge 38 of the latch plate 24 engages a collar 40 fixed on a rod 42 mounted for axial movement on the bracket 30. However, when the latch plate 24 rocks in the counterclockwise direction to a dotted line position (FIGS. 1 and 3) in response to movement of the lever 14, the shoulder 36 is disengaged from the collar 40 permitting the collar 40 and the rod 42 to move rapidly to the dotted line position (FIG. 2) under the urging of a compression spring 44 coiled about the rod between one leg 34 of the bracket 30 and the collar 40.

One end of an actuating cable 46 is suitably held by a bracket 48 fixed to an end of the rod 42 and is guided through a cable housing 50 to an arresting mechanism 52. The cable housing 50 extends from the trigger mechanism 22 at which it is mounted to the support bar 32 by a clamp 53 to the arresting mechanism 52 at which it is

mounted to an upstanding support plate 54 by a clamp 56. An end of the cable 46 opposite the rod 42 is pivotally secured by a suitable wire stop 58 to a swing arm 60 fixed to a stub shaft 62 rotatably mounted on and extending laterally of the support plate 54 which is suitably fixed as by bolts 63 to a laterally extending brace 64 which comprises part of the frame F of the loom.

In response to movement of the rod 42 to the dotted line position (FIG. 2), the cable 46 permits rotation of the swing arm 60 in a counterclockwise direction (FIG. 1) about the stub shaft 62 such that a lower edge 66 of a blade member 68 supported on the swing arm 60 is free to descend into engagement with a warp stop mechanism 70. Of a well known construction, the warp stop mechanism 70 includes a plurality of parallel bars 72 each provided with teeth 74 (FIG. 4) on mutually adjacent edges. During normal operation of a loom having a warp stop mechanism 70, such as the X-2 Model Loom manufactured by Draper Corporation of Hopedale, Mass., each warp yarn supports a blade-like element (not shown) which drops across the bars 72 and engages the teeth 74 upon yarn breakage. One or more of the bars 72 are reciprocated relative to the other bars, but the bars are stopped and operate to stop the operation of the loom when an element engages the teeth 74. The present invention makes use of this construction already available whereby the descent of the blade member 68 in response to operation of the trigger mechanism 22 is effective to stop the loom.

In order to avoid possible damage to any of the mechanism described in the event of a malfunction, a lost motion connection is provided between the blade member 68 and the swing arm 60. More specifically, a pair of spaced apart pins 78 and 80 fixed to the swing arm 60 and extending outwardly from its surface are respectively received in a pair of arcuate-shaped slots 82 and 84, respectively, in the ends of a pair of generally parallel legs 86 and 88 integral with the blade member 68. A tension spring 90 is received between the legs 86 and 88 and connects the blade member 68 to the swing arm 60, to urge terminal surfaces 94 and 96 of the slots 82 and 84 into engagement with the respective pins 78 and 80. In operation, it may occur that the teeth 74 of the warp stop mechanism 70 are not immediately receptive to the lower edge 66 when the actuating cable 46 is extended to permit the blade 68 to drop. For example, at that instant the teeth 74 of one of the adjacent bars 72 may laterally coincide with the spaces in another of the bars with the result that the blade 68 is unable to descend to the extent called for by the cable 46. In this event, the lower edge 66 rests momentarily on upper surfaces of the bars 72 and the swing arm 60 pivots about the pin 78 which engages the terminal surface 94 while the pin 80 slides along the arcuate slot 84, and the spring 90 is extended. When the teeth 74 become receptive to the lower edge 66, the energy stored in the spring 90 is released to restore the blade 68 to its original disposition relative to the swing arm 60 and to draw the lower edge of the blade 68 downwardly between the teeth 74, thereby stopping the loom.

When the magazine 10 has been restocked with a fresh supply of reserve bobbins B and it is desirable to restart the loom, a reset handle 98 fixed to the collar 40 is employed to move the collar 40 against the spring 44 from the dotted line position to the solid line position (FIG. 2) and into engagement by the shoulder 36, the latch plate 24 being rocked in the clockwise direction (FIG. 3) by the torsion spring 28. In the course of this movement, the end of the actuating cable 46 at the arresting mechanism 52 is withdrawn, rotating the swing arm 60 in the clockwise direction (FIG. 1) and moving the blade member 68 to its inoperative position. Should the lower edge 66 of the blade member 68 be seized between the teeth of the warp stop mechanism 70, a condition which might have occurred when the loom was stopped, the swing arm 60 pivots about the pin 80 which engages the terminal

surface 96 while the pin 78 slides along the arcuate slot 82 and extends the spring 90. When operation of the loom is resumed, and the warp stop mechanism 70 releases the lower edge 66, the energy stored in the spring 90 serves to restore the blade 68 to its original disposition relative to the swing arm 60 and to draw the lower edge 66 upward and away from the teeth 74 of the warp stop mechanism 70 in preparation for future actuation.

Although the invention has been disclosed according to a preferred form of construction, it is to be understood that various modifications may be made therein without departing from the spirit or scope of the invention since the scope of the invention is determined solely by the limitations appearing in the appended claims.

What is claimed is:

1. In a loom having a mechanical stop motion mechanism including a plurality of bars which reciprocate relative to one another and are adapted to stop the loom when the relative reciprocation is stopped and a bobbin changing mechanism including a magazine for holding a supply of reserve bobbins, the improvement comprising bobbin sensing means operable for detecting the absence of a bobbin at a predetermined position in said magazine, arresting means including a pivotally mounted swing arm, a blade, lost motion means supporting said blade on said arm and including a pair of spaced apart pins mounted on said arm and said blade having spaced apart slots slidably receiving said pins, and resilient means biasing said pins toward ends of said slots, said blade being pivotable about said pins relative to said swing arm between a first position for releasing the bars and a second position for engaging the bars to stop said relative reciprocation, and actuating means including a trigger mechanism responsive to operation of said sensing means for moving said arresting means to said second position to stop said relative reciprocation.
2. In a loom having a mechanical stop motion mechanism including a plurality of bars which reciprocate relative to one another and are adapted to stop the loom when the relative reciprocation is stopped and a bobbin changing mechanism including a magazine for holding a supply of reserve bobbins, the improvement comprising bobbin sensing means operable for detecting the absence of a bobbin at a predetermined position in said magazine, arresting means movable between a first position for releasing said bars and a second position for engaging said bars to stop the relative reciprocation of the bars, and actuating means responsive to operation of said sensing means for moving said arresting means to stop said relative reciprocation, said actuating means including a trigger mechanism having a rod movable axially between first and second positions, resilient means biasing said rod toward said second position, a collar on said rod, a pivotally mounted latch plate including a shoulder releasably engageable with said collar to hold said rod in said first position, resilient means biasing said shoulder into position for engagement by said collar, and means on said latch plate engageable by said sensing means in the absence of a bobbin for releasing said shoulder from engagement with said collar.
3. In a loom having a mechanical stop motion mechanism including a plurality of bars which reciprocate relative to one another and are adapted to stop the loom when the relative reciprocation is stopped and a bobbin changing mechanism including a magazine for holding a supply of reserve bobbins, the improvement comprising bobbin sensing means operable for detecting the absence of a bobbin at a predetermined position in said magazine, arresting means including a pivotally mounted swing arm, a blade supported on said swing arm and movable between a raised position for releasing the bars and a depressed position for engaging the bars to stop said relative reciprocation, a pair of spaced apart pins fixed to said swing arm, said blade having spaced apart slots slidably receiving said pins, said slots including terminal end sur-

faces, and resilient means biasing said pins toward said terminal surfaces, said blade being pivotable about said pins relative to said swing arm, and actuating means responsive to operation of said sensing means for moving said arresting means to stop said relative reciprocation, said actuating means including a trigger mechanism having a rod movable axially between first and second positions, resilient means biasing said rod toward said second position, a collar on said rod, a pivotally mounted latch plate including a shoulder releasably engageable with said collar to hold said rod in said first position, resilient means biasing said shoulder into position for engagement by said collar, means on said latch plate engageable by said sensing means in the absence of a bobbin for releasing said shoulder from engagement with said collar, and means including a cable connecting said swing arm and said rod to maintain said blade spaced from the bars when

10 said rod is in said first position and to permit said blade to engage the bars when said rod is in said second position.
